UNITED STATES PATENT OFFICE

GUSTAVE ADOLPH NEW, OF PORT CLINTON, OHIO, ASSIGNOR TO AMERICAN GYPSUM COMPANY, OF PORT CLINTON, OHIO, A CORPORATION OF OHIO

GYPSUM WALL BOARD

Application filed March 26, 1928. Serial No. 264,658.

This invention relates to improvements in gypsum wall board, and more particularly to a composite building material consisting of a layer of calcined gypsum or plaster of Paris covered on opposite sides with sheets of paper.

The object of the invention is to provide an improved means of treating the side edges of the board in the course of manufacture in such a manner as to materially improve its structural qualities and its use of the purposes intended.

Wall board or plaster board, as it is sometimes called, is not a new product, and except for variations the methods of forming the edges of the board, treating the materials used, and minor departures in manufacturing processes, the standard practice is to make the board by a continuous process machine, whereby the sheets are fed to the machine from rolls, the wet plaster fed between the sheets and thence between pressure or squeeze rolls which reduce the product to its desired thickness. In some processes of manufacture the edges of the board are open with the full width of plaster exposed, although the more recent practice has been to cover or bind the edges by folding the margins of one or both covering sheets over the side edges—either completely or partially sealing the plaster body at the side edges. Again, wall board is manufactured with the margins of the covering sheets embedded in the edges of the plaster core or body, thus providing additional reinforcement to strengthen the edge and to give three or more plies of paper through which the nails are driven when applying the board to the wall.

The present invention seeks to improve upon the various types of edge construction heretofore used or now in use, by retaining the advantages of an edge covering and reinforcement but without the attending disadvantages; the chief of which is the weakening of the core material along the edges of the board when there is a complete or substantially complete coverage of the edge with paper. As well known in the art, the board is dried in the process of manufacture to drive off the moisture in the wet plaster and

since the paper covering on the edges tends to retard the drying, it is necessary to either prolong the drying process or to increase the temperature in the drying kilns. In either case, there is the attendant possibility of excessive calcination of the plaster, particularly at the edges with the result that they become quite brittle and therefore easily fractured. This condition is more pronounced along the edges than elsewhere, since the edge portions are exposed to the heat on three sides.

It is proposed therefore to eliminate paper or like fibrous material for the covering and reinforcing material and use a woven mesh fabric, such as cloth or fine wire, the former being quite satisfactory for practical purposes.

The following is a description of the manner in which wall board is constructed in accordance with my invention together with a disclosure of a practical method of manufacturing such a product:

In the accompanying drawings,

Figure 1 is a view in cross section through the edge of a piece of wall board showing the preferred method of disposing the covering and reinforcing material at the edge.

Figure 2 is a perspective view of a piece of wall board with portions broken away at its edge to show the disposition of the fabric more clearly.

Figure 3 is a perspective view of a length or strip of fabric showing the manner in which it is folded prior to and during its introduction into the edges of the board, and

Figures 4 and 5 are cross sectional views similar to Figure 1, showing modified edge constructions for wall board using a fabric covering or reinforcement.

As clearly shown in Figures 1 and 2, the wall board embodying the invention consists of a central core or body 1 of plaster, that is, calcined gypsum, and top and bottom covering sheets 2, 2 of paper of the kind and quality ordinarily used for this purpose. The edges of the paper preferably coincide with the edges of the plaster body, thus leaving the full thickness of the plaster body exposed along the side faces of the board, except for the covering material applied thereto. To

the edge or edge faces is applied a layer of fabric extending the full width thereof; this fabric, as will presently be seen, having the form of a narrow strip or tape 3 which is applied along the edges in the process of manufacture. Moreover, the fabric covering strip includes an inwardly projecting portion 3a extending at right angles to the edge faces midway between the covering sheets. 5

10 This inwardly extending portion is made up of two plies of the fabric, generally formed by folding the strip double, embedding the folded edge portion edgewise into the open edge of the board and midway of 15 its thickness, with protruding marginal portions 3b, 3b of sufficient width to be folded in opposite directions and cover the exposed edge face of the plaster core on either side of the embedded portion of the strip. 20

Considering the material as a continuous strip of woven mesh fabric, the same assumes the shape of a T, with its base portion 3a of double thickness extending edgewise into the core a distance of from $\frac{3}{4}$ to 1 inch, 25 thus providing a reinforcement for the edge and two plies of fabric through which the nails are driven in applying the board to a wall, and the two edge portions 3b, 3b of a single thickness, folded at right angles to 30 the embedded portion 3a and laid flatwise against the exposed faces of the body, with their outer edges coinciding with the edges of the covering sheets. Inasmuch as the 35 plaster body is in wet or plastic condition when the fabric strips are inserted and applied, the pressure exerted along the edge of the board forces the wet plaster through the interstices of the mesh thus firmly embedding the material in the plaster and leaving a smooth finished surface at the edge. 40

While a number of practical methods may be used for manufacturing a board of a kind such as described, the following is believed to be as satisfactory as any: Assuming that the 45 wall board is to be of the standard thickness of $\frac{3}{8}$ of an inch, the width of the mesh fabric used would be about 2 inches. The fabric would be wound in rolls either single or folded double, and fed therefrom in the same 50 manner as the paper covering sheets. The material itself is relatively inexpensive not unlike cheese cloth or cheap muslin, which has been starched or sized to make it fairly stiff—in fact, it may be material of the same 55 character used in the lining of garments.

Figure 3 is a diagrammatic illustration of the manner in which a strip of single thickness mesh fabric would be inserted into the edge of the board as made by the continuous 60 process. The material is fed from rolls mounted on suitable spindles located adjacent the point where the material enters the wet plaster. On leaving the rolls as a flat band or strip as at A, (Figure 3) it would 65 first pass through suitable folders which

would fold it double with its folded edge inwardly and the free edges outwardly, as at B, the stiffness of the material making it readily foldable with a sharp crease only at its folded edge as at b. By means of guide rolls the folded strip would then be led horizontally between the edges of the two covering sheets and into the mass of wet plaster between the two, so that the greater portion of the folded strip would be embedded in the plaster as the materials passed between the forming rolls. The free edge portions of the fabric strip would project outwardly from the edges of the plaster body, and immediately after the board had left the forming rolls, a spreading finger would be encountered which would separate the two protruding edges of the fabric and fold them back at right angles and in opposite directions against the edge of the board above and below the embedded portion, as at C. A pressure roller would be located just beyond the spreading finger or member to press the fabric into the edge and otherwise produce a square and finished edge surface. While Figure 3 shows the successive folded positions of a continuous strip of the mesh fabric from the time it leaves the roll to its incorporation in the board, it is understood that each folding operation would take place in its proper relation to the progress of the board through the manufacturing process, with the proper guides and folding devices to control the strips at either edge of the board. In case the mesh fabric is initially in double folded form as at B, it would then be introduced directly into the edge of the board and then folded into T form as at C. 70

It is preferred to form a groove 4 in the edge face of the board at the junction of the embedded portion 3a of the fabric strip and the two edge portions 3b, 3b (Figure 2), this groove being formed by a suitable pointed grooving tool mounted in the path of the edges of the board and pressing into the surface while the plaster mass is still wet. Such a groove is advantageous as a means of holding the crack-filling material, which is usually applied along the joint between the edges of two wall boards, when nailed to a 75 wall. The grooves fill with the plastic crack-filling material to form keys which prevent the same from falling out after it has dried. 80

Wall board provided with a fabric covered edge is superior to the paper covered edge, in that the fabric is of ample strength to give the required reinforcement and coverage at the edge, and yet is sufficiently porous to permit the plaster to pass therethrough, not only 85 affording a perfect bond between the two materials but allowing the moisture to escape freely during the drying process. In fact, the fabric exhibits a pronounced catalytic action on the plaster by promoting the crystal 90

formation on setting and thus further tending to increase the strength of the plaster at the edge.

Aside from the manner of using and introducing a fabric covering and reinforcing material into the edge of wall board already disclosed, other ways and means may be readily devised and adopted. For instance, Figure 4 shows a strip 5 of fabric folded in U-shape instead of T-shape and inserted in somewhat the same manner into the edge of the board. In this form the edge portions 5a, 5a of the strip extend into the plaster body just beneath the edges of the covering sheet. Again in Figure 5, two narrow strips 6, 6 may be introduced into the edge instead of the single U-shaped strip as in Figure 4. In this instance the outer edges of the strips may meet along the center line of the edge face, either with a narrow space between, in abutting contact or overlapping so that there is a double thickness of fabric over part or the entire width of the edges.

Having set forth a preferred embodiment of my invention,

I claim:

1. A wall board comprising a plaster body, covering sheets of fibrous material extending over the top and bottom faces of said body and a strip of mesh fabric applied over the edge face of said body and having a portion thereof extending into said body.

2. A wall board comprising a plaster body, covering sheets of fibrous material extending over the top and bottom faces of said body and a strip of mesh fabric applied along the edge face of said body and having a portion thereof folded double and embedded in said body at right angles to said edge face.

3. A wall board comprising a plaster body, covering sheets of fibrous material on the opposite faces of said body, and strips of mesh fabric applied to the side edge faces of said body and having sections folded to project laterally into said body for a predetermined distance.

4. A wall board comprising a plaster body, covering sheets of fibrous material on the opposite faces of said body, and a strip of mesh fabric applied to a side edge face of said body and consisting of a portion folded double and extending edgewise into said body for a predetermined distance, and marginal portions folded over against the edge face of said body.

5. A wall board comprising a plaster body, covering sheets of fibrous material on the opposite faces of said body, and a strip of relatively stiff mesh fabric folded into substantially T-form, with one portion of double thickness extending edgewise into said body substantially midway its thickness and the remaining portions folded in opposite directions against the edge face of the body.

6. A wall board comprising a plaster body,

covering sheets of fibrous material on the opposite faces of said body, and extending to the side edges thereof, and strips of relatively stiff mesh fabric folded into substantially T-form and applied along the side edges of said body, with one portion of double thickness extending edgewise into said body substantially midway its thickness and the remaining portions folded back and pressed into the edge face of the body.

7. A wallboard comprising a plaster body, covering sheets on opposite sides of said body and terminating at the side edges thereof, and a strip of mesh fabric folded in substantially T-form and applied to the edges of said body with one portion at the edge surface and the other portion extending edgewise into said body.

8. A wallboard comprising a plaster body, covering sheets on opposite sides of the body and terminating at the side edges thereof, and a strip of mesh fabric applied to said edges, said fabric being folded to provide a portion of substantially the width of the edge face of said body, and a portion extending at right angles to said first mentioned portion and extending edgewise into said body.

9. A wallboard comprising a plaster body, covering sheets of fibrous material on opposite faces of said body and terminating at the edges thereof, and a strip of mesh fabric folded longitudinally upon itself in T-section and applied to the edges of said body with one portion adhering to the same and the other portion extending laterally into said body.

10. A process of manufacturing wallboard consisting of continuously advancing sheets of covering material toward a pair of pressure rolls, feeding wet plaster into the lower covering sheet in advance of said pressure rolls, feeding a strip of woven mesh fabric toward the advancing edges of said covering sheet, folding said strip longitudinally as it is being fed to provide an edge portion of double thickness, guiding said strip into the path of the advancing edges of said covering sheets and plaster, whereby said edge portion of the strip is embedded edgewise in the plaster and flattening the remaining portion of the strip against the edge faces of the plaster.

11. A process of covering the edges of said wallboard in the course of manufacture by a continuous process consisting of feeding strips of mesh fabric from rolls toward the path of the advancing edges of the board, folding the strips double, guiding said folded strip edgewise into the edges of the board with the free edge portions extending outwardly therefrom, and spreading the projecting edge portions against the edge faces of the plaster.

12. A process of covering the edges of

- wallboard in the course of manufacture by a continuous process consisting of feeding strips of narrow mesh fabric from rolls toward the path of the advancing edges of the board, folding the strips longitudinally as they are advanced, guiding said folded strips edgewise into the path of the edges of the board so that their inner edge portions are embedded in the plaster and flattening the outer marginal portions against the edge face of the plaster.
13. A plaster board comprising a plaster core, top and bottom covering sheets, and a fabric strip adhered to the edge of the core, said strip having a lateral member extending into and anchored in the core.
14. A wallboard comprising a plaster body, sheets of fibrous material covering the top and bottom faces of said body and a strip of mesh fabric folded to provide angularly disposed portions, one of single thickness being applied parallel to the edge face of said body and another of double thickness extending edgewise into said body.
15. A wallboard comprising a plaster body, sheets of fibrous material covering the top and bottom faces of said body and a strip of mesh fabric folded longitudinally to form angularly disposed portions, one portion of single thickness being equal in width to that of the edge face of said body and applied over the same, and the other being of double thickness and extending edgewise into said body from its edge face.
16. A wallboard comprising a plaster body, sheets of fibrous material covering the opposite faces of said body and terminating at the edges thereof, and strips of mesh fabric folded lengthwise to form angularly disposed portions, one portion being of double thickness and extending edgewise into said body substantially midway of its thickness, and the other portion of single thickness being applied against the edge face of said body between the edges of said sheets.
17. A wallboard comprising a plaster body, covering sheets of fibrous material on the opposite faces of said body, and a strip of mesh fabric applied along the edge face of said body and consisting of a portion folded double and embedded edgewise into said body, and portions of single thickness extending at right angles to said first-mentioned portion and applied to said edge.
18. A wallboard comprising a plaster body, covering sheets of fibrous material on the opposite faces of said body, and a strip of relatively stiff mesh fabric folded longitudinally into substantially T-form, with one portion of double thickness extending edgewise into said body substantially midway its thickness, the remaining portions of single thickness extending in opposite directions and applied to the edge face of the body throughout its width.
19. A wallboard comprising a plaster body, covering sheets of fibrous material on the opposite faces of said body, and extending to the side edges thereof, and strips of relatively stiff mesh fabric folded into substantially T-form to provide a portion of double thickness extending edgewise into said body substantially midway its thickness and portions of single thickness extending in opposite directions from said first-mentioned portion and applied to the edge face of the body.
20. A process of treating the edges of wallboard being made by a continuous process, consisting of feeding a strip of mesh fabric toward an edge of the advancing board, folding the advancing strip along a median line to form a marginal portion of double thickness, guiding the double folded portion edgewise into the edge of said board so that it is embedded in the plaster therealong, and applying the remaining portion of the strip against the edge face of the board.
21. A process of manufacturing wallboard consisting of continuously advancing sheets of covering material toward a pair of pressure rolls, feeding wet plaster upon the lower covering sheet in advance of said pressure rolls, feeding strips of mesh fabric toward the edges of the advancing board, folding the advancing strip longitudinally to form a portion of double thickness, guiding said folded strip into the edge of said advancing board with said portion of double thickness foremost and disposed edgewise, and applying the remaining portions of said strip to the edge faces of the plaster.
22. A process of reinforcing the edges of wallboard in the course of manufacture by a continuous process consisting of continuously feeding strips of mesh fabric toward the path of the advancing edges of the board, folding the strips as they are advanced to provide a marginal portion of double thickness, guiding said folded strip into the edges of the board with the portion of double thickness entering the plaster edgewise, and applying the remaining portions of the strips against the edge faces of the plaster.
23. A process of covering an edge of wallboard in the course of manufacture by a continuous process consisting of feeding a strip of narrow mesh fabric from a roll toward the path of an advancing edge of the board, folding the strip longitudinally as it is advanced, guiding said folded strip edgewise into the path of the edge of the board so that its inner folded edge portion is embedded in the plaster, and flattening its outer marginal portions against the edge face of the plaster.

Signed at Port Clinton this 21st day of March, 1928.

GUSTAVE ADOLPH NEW.
